UNITED STATES PATENT OFFICE

WILLIAM J. WRIGHT, OF OVERLEA, BALTIMORE, MARYLAND

BOOK-IDENTIFICATION DEVICE

Application filed December 1, 1928. Serial No. 323,166.

This invention relates to identification devices and more particularly devices of this character which are adapted to be secured upon books and paper binders as disclosed in my application Serial No. 247,448, filed January 17, 1928, Patent No. 1,698,663, Jan. 8, 1929, and upon which this invention constitutes an improvement.

One of the objects of this invention is to provide a device of the character disclosed in the above named application, in a manner as hereinafter set forth, wherein the identification indicia carried thereon may be expeditiously changed at will.

Other objects of the invention are to provide, in a manner as hereinafter set forth, a device of the aforementioned character which will be simple in construction, durable, efficient in its use and which may be manufactured at low cost.

Other objects and advantages of this invention will be apparent from a study of the accompanying drawings taken in connection with the following specification.

In said drawings Figure 1 is an elevation of the device mounted on a binder.

Figure 2 is a view taken centrally through the binder showing the manner of securing my device thereon.

Figure 3 is a perspective view of the invention.

Figure 4 is a side view thereof partly in section.

Figure 5 is a transverse sectional view.

Figure 6 is an end view of the device.

Referring to the drawings in detail, reference character 1 indicates a binder of conventional type having secured therein by retaining strips 2 a plurality of sheets 3.

The device constituting this invention comprises an elongated strip 4 of any suitable material, having its opposite ends turned at right angles thereto and forming transversely extending lugs 5 and 6. The lug 5 is provided

6 is provided with an inwardly tapered opening 8. The openings 7 and 8 are located near the free end of the lugs 5 and 6.

A detachable securing bar 9 is supported at its opposite ends in the openings 7 and 8 upon the lugs 5 and 6. One end of the bar 9 is provided with a permanent sleeve 10 having an outwardly flanged end 11. The bar 9 is threaded through the sleeve 10 and provided with an upset end 12 for the purpose of preventing said bar from being separated from said sleeve.

The opposite end of the bar 9 is provided with threads 13 upon which is mounted a detachable securing device 14. The securing device 14 is provided with a transversely slotted tapered head 15 adapted to seat in the opening 7 of the lug 5.

Intermediate its ends the strip 4 is provided with pairs of opposed incisions 16 and 17 which extend transversely into said strip 4 for a distance from the longitudinal edges thereof. The marginal portions of the strip 4 lying between the pairs of incisions 16 and 17 are turned back to form opposed, groove-forming flanges 18. The lower ends of the flanges 18 are bent down against the face of the strip 4 for the purpose of closing that end of the grooves formed by said flanges, as shown by reference character 19. The grooves at the opposite ends of the flanges 18 are open to permit the insertion of an indicia bearing strip 20 into the grooves formed by the flanges 18. The strip 20 may be formed of any suitable material such as cardboard or thick paper. A strip of transparent material 21 is positioned under the flanges 18 and over the strip 20 for the purpose of protecting same.

In use the bar 9 having sleeve 10 thereon and securing device 14 are removed from the strip 4. The strip 4 is then positioned upon the rear end of a binder in the manner shown in Figures 1 and 2 of the drawings, in which position the lugs 5 and 6 will extend forward.

ly over the upper and lower edges of the leaves in said binder. The securing rod 9 and securing sleeve 10 are then projected through the opening 8 in lug 6 and passed through the binder forwardly of the strips 2 into the opening 7 of lug 5. The securing device 14 is then screwed onto the threads 13 on rod 9 through the opening 7 until the tapered head 15 of said securing device seats in said opening. In this position the device is securely mounted upon the binder.

The indicia bearing strip 20 together with the protecting strip 21 is then inserted under the flanges 18 through the open upper ends 15 thereof and slid downwardly thereunder until arrested by the turned-down ends 19 of said flanges. Should it be desired to change the identification indicia on the device this may be accomplished by simply sliding the strips 20 and 21 upwardly from under the flanges 18 and replacing the strip 20 with one bearing the desired indicia as will be obvious.

It is thought that the many advantages of an identification device for binders which is 25 constructed in accordance with this invention can be readily understood, and although the preferred embodiment of the invention is as illustrated and described, it is to be understood that changes in the details of construction can be had which will fall within the scope of the appended claims.

What I claim is:—

1. A device of the character described comprising an elongated metal strip, means 35 carried by said strip for removably securing same on a binder, said means comprising transversely extending lugs having openings therethrough on the respective ends of said strip, a securing rod mounted in said openings and having a permanently attached sleeve on one end adapted to seat in the opening of the adjacent lug and a removable sleeve on the opposite end adapted to seat in the opening in the other lug, and identification 45 indicia retaining means carried by said strip intermediate its ends, said means comprising spaced opposed groove-forming flanges having one end turned down into engagement with the elongated strip and the opposite end 50 open for the reception of removable identification indicia thereunder.

2. A device of the character described comprising a strip having spaced apertured lugs, a securing rod having its opposite ends 55 mounted in the aperture in the lugs and, in conjunction with said lugs, constituting means for securing the strip on a binder, said strip further having turned-back groove-forming marginal portions for securing indicia-bearing means upon the strip.

3. A device of the character described comprising a strip having apertured lugs at its opposite end, a detachable rod having its ends mounted in the apertures and secured 65 on the lugs, said rod, in conjunction with

the lugs, constituting means for securing the strip on a binder, said strip being further provided, at a point intermediate of and spaced from the lugs, with turned-back marginal portions constituting groove-forming flanges for securing indicia-bearing means on the strip, each of said flanges having an end portion directed toward the strip in a manner to close an end of the grooves.

In testimony whereof, I affix my signature hereto.

WILLIAM J. WRIGHT.
